SHIRT AND METHOD FOR ATTACHING
LABELS THERETO

Jacob Friedmann, Freeport, N. Y., assignor to
H. D. Rob Company, Inc., New York, N. Y., a
corporation of New York

Application August 31, 1934, Serial No. 742,332

5 Claims. (Cl. 2—115)

This invention relates to the construction of garments and more particularly to shirts and method for attaching labels thereto.

In the shirt constructions of the prior art, it has been customary to provide a shirt with a yoke which is generally of two thicknesses. The inner thickness of yoke material has a label attached to it before it is put into the garment. The stitching for fastening the label goes through this single thickness but when the two pieces which comprise the yoke are combined the back stitching of the label is hidden by the second thickness. This method of attaching the label can be used only when the label is sewed into place before the parts of the garment are assembled.

When attaching the label to the yoke before assembling the usual practice required stitching the label along four sides each of which had to be turned under to present a finished edge. This is a time consuming operation in which considerable care has to be exercised to properly space and finish the edges of the label.

It often happens that a shirt and garment manufacturer could continue production if it were not for the fact that he did not at the moment know to which customer a particular group of shirts would be consigned since he might not then have any standing orders. It was accordingly necessary for him under such circumstances to limit his production since he could not omit the labels from the shirt and later sew them in because by so doing the label stitching would show through the second thickness of the yoke causing an unsightly appearance and branding the garment as one of inferior quality.

It is, therefore, among the objects of the present invention to provide a method and a garment structure whereby the label might be attached either in the normal process of manufacture or at any subsequent time.

It is also an object to provide a construction for shirt garments so that if an order has been cancelled or if the wrong label has been used it could be removed from the garment and replaced by a proper label without branding the garment as a second or in any other way causing deterioration in its general appearance.

It is an important object of this invention to provide a label which acts not only as a designation of the source of the garment but also has the additional function of providing a hanger.

A further object is to provide a method for attaching labels to garments which may be used on shirts of either the neck band or collar attached type.

These and other objects which will be apparent from the sequent description are all embodied within the scope of this invention, a preferred embodiment of which is illustrated in the accompanying drawing, in which:

Fig. 1 is a front view showing a garment with the collar opened to reveal the attached label;

Fig. 2 is a sectional view along the line II—II of Fig. 1; and

Fig. 3 is a view showing the label used as a hanger.

Referring now more particularly to Fig. 1 of the drawing, 2 designates a garment or shirt generally which is constructed of a back 4, a yoke 6, and a collar or neckband 8 combined in the usual approved fashion for constructing garments and more specifically shirts. In the center of the yoke 6 is a label 10 which it will be noted is exposed between the seam 12 joining the back 4 and the yoke 6 and the seam 14 joining the collar 8 or a neckband and the yoke 6.

The label having suitable indicia thereon is generally produced in long strips of a series of labels one above the other with finished non-ravelling selvedges although they might be produced individually with the vertical edges finished. Usually two edges of the labels and in the illustrated embodiment the top and bottom edges are not finished nor need they be finished since they are covered and prevented from unravelling when the labels are attached by the seams or seam stitchings of the garment. When the garment is being assembled and particularly when the two seams 12 and 14 are stitched the label is also attached to the garment with stitching at each end. It will thus be seen that the label is attached without any additional lateral or vertical stitching but simply by the normal stitching necessary to complete the seams of the garment whereby the time for completing a garment and the cost is reduced.

Since the label is laid flat against the yoke and is attached at the top and the bottom by constructional seams or seam stitchings of the garment it normally lies flat against the yoke but due to the fact that there is no stitching along two sides, the label may be separated in its intermediate portion from the yoke and thus provide a loop useful as a hanger for the garment. This is illustrated in Fig. 3 wherein the hook 20 is shown supporting the garment by means of the label 10.

The method of attaching the label is more specifically illustrated in the sectional view, Fig. 2. The yoke 6 as generally constructed comprises

an outer piece 16 and an inner piece 18 which is attached to the back 4 along one side by a seam 12 and to the collar 8 or a neckband along the other side of the yoke by a seam 14. The inner 5 member of the yoke 18 has a small portion of it covered by the label 10 which may also be turned over at each end and attached to the collar and back in the same fashion as the yoke member 18 by seam stitchings 12 and 14.

10 It will be appreciated that various other constructions for attaching the yoke members to the back and to the collar may be employed but that whatever method of construction may be used there will always be a seam at these junctures 15 and these seams can be employed to attach the label.

In the event that a manufacturer is producing shirts for which he has no particular designation and therefore cannot insert a label, he may 20 complete the garment without the label either omitting the stitches in the label position or continuing the stitches all along these seams and then later readily attach a label of the type disclosed herein by inserting a label into the unsewed portion of the seam or ripping the seams 25 10 and 12 for a short distance in the position where the label is to be attached, insert the label and complete the seams. This can readily be done without showing any alteration of the garment.

If a manufacturer has prepared a lot of shirts with one label and due to cancellation of orders or other reasons finds it necessary to change the 35 label, this can be easily accomplished in the same manner as described above except that one label is removed and replaced by the desired one.

From the foregoing it will be understood that this invention provides a new method of garment 40 construction and more particularly a new and useful method and construction for easily and cheaply attaching labels to shirts in which the

label not only acts as a designation of source but is also useful as a hanger.

Having thus described the invention, what I claim as my invention is:

1. A garment construction comprising a collar, a yoke and a back, a seam joining the collar to the yoke, another seam joining the yoke to the back and a label attached at one end by the seam stitching joining the collar and the yoke and at the other end by the seam stitching joining the 10 back to the yoke. 5

2. A shirt construction comprising a neckband, a yoke and a back, a seam joining the neckband to the yoke, another seam joining the yoke to the back and a label attached at one end by the seam stitching joining the neckband and the yoke and at the other end by the seam stitching joining the back to the yoke. 15

3. A garment construction comprising a collar, a yoke and a back, a seam joining the collar to the yoke, another seam joining the yoke to the back and a label with one end inserted into the 20 seam joining the yoke and the back, and the other end inserted into the seam joining the yoke to the collar, held in place by the seam stitchings and with its ends hidden within the seam. 25

4. A garment construction comprising a collar or neckband, a yoke, and a back, a seam joining the collar or neckband to the yoke, another seam joining the yoke to the back and a label attached to said garment at one end at the seam joining 30 the collar and the yoke and at the other end at the seam joining the back to the yoke. 35

5. A garment construction comprising a collar or neckband, a yoke, and a back, constructional 35 seams joining the collar or neckband to the yoke and the yoke to the back, a label attached to the garment by the stitchings of the said constructional seams and unattached along two sides to provide a label which serves as a designation of 40 source and also as a hanger.

JACOB FRIEDMANN.
